UNITED STATES PATENT OFFICE.

EDWARD P. LE COMPTÉ, OF PARK CITY, UTAH.

BLACKING-BRUSH.

SPECIFICATION forming part of Letters Patent No. 684,059, dated October 3, 1899.

Application filed November 7, 1898. Serial No. 695,760. (No model.)

To all whom it may concern:

Be it known that I, EDWARD P. LE COMPTÉ, a citizen of the United States, residing at Park City, in the county of Summit and State of Utah, have invented certain new and useful Improvements in Blacking-Brushes; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to blacking-brushes, and its object is to provide an improved construction of the same, with means for removing mud and dirt from boots and shoes, whereby the dauber and polishing-brushes will not be soiled.

The features of construction of my improvement will be fully described hereinafter, and defined in the appended claims.

In the accompanying drawings, Figure 1 is a perspective view of a blacking-brush constructed in accordance with my invention. Fig. 2 is a side elevation, the mud-brush being removed. Fig. 3 is a view of the scraper removed.

In the said drawings the reference-numeral 1 designates an ordinary blacking-brush, comprising the block 2, provided on its under side with the polishing brush or bristles 3 and on its upper side with the handle 4 and dauber 5. The parts so far described may be of any ordinary or suitable construction.

The block 1 upon one side at the front end is cut away, and secured to said cut-away portion is a mud or dirt brush 6. Located on the upper side of said block 1 is a movable scraper 7, consisting of a flat metal bar 8, having its inner end bent outward at an angle, forming an operating-lug. This bar is held in place on the block by a guide 9 and curved spring 10, secured to the under side of the dauber, with its ends resting upon the bar

and by the tension of which the bar is held in place on the block. The outer end of said bar is formed with an enlarged rectangular head 12, formed with a slit 13 and bent at a right angle, so as to form a scraper, whereby mud and dirt may be removed from a boot or shoe, the corners or points of said plate rendering it especially efficient in removing dirt from between the sole and the upper.

The manner of using the device will be readily understood. When not in use, the scraper is pushed in, so that its head will be flush with the end of the brush. When it is desired to use the brush, the scraper-bar is pushed outward, so that the head thereof can be used to scrape off mud and dirt from a boot or shoe. The mud-brush is then employed to brush off the mud and dirt loosened by the scraper, when the dauber and polishing-brush can be used in the ordinary manner.

Having thus fully described my invention, what I claim is—

1. In a blacking-brush, the combination with the block, polishing-brush and handle, of the dauber, a mud-brush, a movable scraper, a spring secured to the dauber and having its ends bearing upon the scraper, and a guide secured to the block for supporting the movable scraper.

2. In a blacking-brush, the combination with the block, the polishing-brush, the handle, the dauber and the mud-brush, of the movable scraper-bar, having an enlarged rectangular head at the outer end slitted and bent at a right angle to the bar, the guide, and the spring secured to the dauber with its ends bearing upon said bar, substantially as described.

In testimony whereof I affix my signature in presence of two witnesses.

EDWARD P. LE COMPTÉ.

Witnesses:

WILSON I. SNYDER,
ZETTA FARNSWORTH.
